DRAWER FOR A SHOE CHEST

Arthur G. Cashman, 8320 Oxon Hill Road,
Washington, D.C. 20022

Filed May 22, 1967, Ser. No. 7,226

Term of patent 14 years

(Cl. D33—1)

FIG. 1 is a perspective view of a drawer for a shoe chest, showing my new design, the front of the drawer being shown as closed;

FIG. 2 is a vertical sectional view, taken substantially in the plane of the line 2—2 in FIG. 1; and

FIG. 3 is a perspective view of the drawer with the front thereof in the open position.

The undisclosed side and back of the drawer are conventional.

I claim:

The ornamental design for a drawer for a shoe chest, as shown and described.
